UNITED STATES PATENT OFFICE.

CARL F. JOLITZ, OF PINE ISLAND, MINNESOTA.

ICE-CREEPER.

SPECIFICATION forming part of Letters Patent No. 767,565, dated August 16, 1904.

Application filed August 31, 1903. Serial No. 171,450. (No model.)

To all whom it may concern:

Be it known that I, CARL F. JOLITZ, a citizen of the United States, residing at Pine Island, in the county of Goodhue and State of Minnesota, have invented a new and useful Ice-Creeper, of which the following is a specification.

This invention relates to boots and shoes, and particularly to the manner of applying antislapping devices to rubber soles and heels.

Owing to the consistency of the rubber, the ordinary fastening devices, such as screws and the various styles of clamps, cannot be advantageously employed in connection with the antislapping devices as applied to rubbers, as the rubber is not sufficiently rigid to retain the fastening devices.

It is particularly the object of this invention to construct an antislapping device which will be inexpensive and easy to apply to the shoe and to provide an efficient means for fastening the device to the shoe.

With these and other objects in view the invention consists in certain novel features of construction, which will be specifically set forth in the following description, reference being had to the accompanying drawings, in which—

Figure 1 is a perspective view of the blank for the preferred form of the device. Fig. 2 is a perspective view of the device with the calks bent up. Fig. 3 is a sectional view through a portion of a shoe and an antislapping device. Fig. 4 represents a perspective view of a slightly-modified form of antislapping device. Fig. 5 represents a detail sectional view.

The preferred form of the invention is illustrated as comprising two limbs 1 and 2, terminally connected by an intermediate and curved portion 3, resembling in form a horse-shoe, having terminal calks 4 and 5 and an intermediate calk 6. In practice this form

of the antislapping device will be die-struck of a single piece of metal and will have the calks bent by a suitable former so as to have them outstanding for engagement with the surface.

The means of fastening the device to the heel of the shoe or boot consists of a head or plate 10, with integral depending shanks 10^a, adapted for insertion into the antislapping device, and the shoe will be clamped between the antislapping device and the head or plate, so that there will be no danger of the fasteners pulling through. Owing to the peculiar formation of the shanks or integral projections 10^a and by reason of their being of no greater diameter than the openings in the calk-carrying plate, said plate can be moved upon the shanks so as to firmly secure the shoe-heel between them, and the rivet-heads may then be provided by upsetting the terminals of the shanks.

In the modified form of antislapping device (illustrated in Fig. 4) the rear calk is dispensed with and in its stead two spurs 11 and 12 are employed, which serve to prevent any displacement or slipping of the shoe.

I claim—

In an antislapping device, two members, one of which comprises a plate having projections and openings and the other member comprising a plate having depending integral shanks to enter the openings in the first-mentioned plate, the said first-mentioned plate being free for uninterrupted clamping movement on the shanks, and upsettable terminals on the shanks to secure the two plates together.

In testimony that I claim the foregoing as my own I have hereto affixed my signature in the presence of two witnesses.

CARL F. JOLITZ.
